DESIGN FOR A PLAY POOL

William I. Smith, Perrysburg, Ohio, assignor to
The Hettrick Manufacturing Company, To-
ledo, Ohio, a corporation of Ohio

Application July 27, 1938, Serial No. 78,781

Term of patent 7 years

To all whom it may concern:

Be it known that I, William I. Smith, a citizen of the United States and a resident of Perrysburg, Wood County, Ohio, have invented a new, original, and ornamental Design for a Play Pool, of which the following is a specification, reference being had to the accompanying drawing, forming a part thereof.

In the drawing:

The figure is a perspective view of the play pool showing my new design.

The characteristic features of this invention reside in a play pool having side walls of rectangular formation with post braces arranged

to form a V at each corner; and a bench arranged at one side of the pool having curved end frame members defining the seat portion of the bench as a continuation of the top edge of the pool and defining a substantially vertically extending back, and a back rest of rectangular formation which is proportionate to the rectangular side walls of the pool, supported on said end frame members as shown.

I claim:

The ornamental design for a play pool, as shown and described.

WILLIAM I. SMITH.
